UNITED STATES PATENT OFFICE.

PHINEAS L. BARTHOLOMEW, OF AURORA, ILLINOIS.

PAPER-BAG-MAKING MACHINE.

1,283,454.

Specification of Letters Patent.

Patented Nov. 5, 1918.

Application filed May 22, 1918. Serial No. 235,952.

To all whom it may concern:

Be it known that I, PHINEAS L. BARTHOLOMEW, a citizen of the United States, residing at Aurora, in the county of Kane and State of Illinois, have invented new and useful Improvements in Paper-Bag-Making Machines, of which the following is a specification.

This invention relates to paper bag making machines, and more particularly to those machines of the rotary type and in which a diamond fold is formed for the bottom of each bag, the body of the latter being formed of a bellows folded tube.

Among the objects of my invention is to improve the construction of machines of the kind referred to in the several particulars as will hereinafter more fully appear, and to provide in particular improvements in that portion of the machine which makes and forms a diamond fold for the bottom of the bag. Another object of my invention is to so construct and arrange the parts of the machine that the latter may be operated at a very high rate of speed and thus enable the formation and turning out of completed bags at a very rapid rate. A further object of my invention is to provide means for accurately and positively guiding the paper tube to the gripper rolls and also to hold the tube against lateral and other displacement as the tube is fed to the gripper rolls, so that the gripper mechanism of the latter may be able to properly grip the portions of the paper tube at the desired places and thus permit the making of perfect bags. From this it follows that the formation of imperfect bags is effectively guarded against and thus waste avoided. This is an essential advantage in machines of this character, because, inasmuch as they are operated at a very high rate of speed and produce and turn out completed bags at a very rapid rate, it follows that the operator is unable to detect an imperfect bag at the time that it is initially formed. The bags being formed at such a rapid rate, the operator cannot detect the formation of imperfect bags until a great number of them have been completed and the first one delivered from the machine. At such time the operator stops the machine in order to adjust the paper tube being fed thereto, and is required

to waste that portion of the material in the machine which has been converted into imperfect bags. With a machine constructed in accordance with my invention I am enabled to guard against such waste and thereby enhance the effective output of the machine. A further object of my invention is to so construct the gripper mechanism of the gripper rolls that they act positively and with firmness and open and close at the required time to grip and release the interposed portions of the paper tube. A still further object of my invention is to so construct the gripper mechanism that certain parts thereof are moved toward and from each other for the purpose of gripping and releasing the interposed portions of the paper tube, and to provide such a construction that, in case the machine should be operated without any stock being fed thereto, such portions of the gripper mechanism will not pound or contact against each other and thereby avoid the crystallization and ultimate breaking of such parts. A still further object of my invention is to place one of the sets of cutting knives in the feed rolls positioned beyond the gripper rolls so as to permit the entrance of guide and stripping wires into annular grooves in the gripper rolls, and thereby prevent the paper tube from being carried around with such gripper rolls in case the paper tube should become attached to such gripper roll by an adhesive or other substance that may become adhered to such gripper roll. A still further object of my invention is to provide a set of cutting knives in one of the gripper rolls so that the layer of the paper tube provided with the lip or tongue may be completely severed from the tube and thus permit such tongue to be raised into position for engagement by the grippers provided for that part. Another object of my invention is to so construct and mount the spreader arms and ironer plates that all of such parts may be swung bodily outward away from the gripper rolls by a manual operation in order to permit the operator to gain access to the portions of the gripper rolls immediately behind such parts, as would be required in feeding the paper tube initially into the machine, or in case the tube should become buckled or otherwise folded during the op-

eration of the machine, when it is necessary to stop the machine and gain access to the parts for the purpose of removing such hindrance or obstruction.

5 The invention consists further in the matters hereinafter described, and more particularly pointed out in the appended claims.

In the accompanying drawings—

Figure 1 is an elevational view of one side 10 of a paper bag making machine constructed in accordance with my invention;

Fig. 2 is a top plan view of said machine;

Fig. 3 is a front elevational view of said machine;

15 Fig. 4 illustrates the train of gearing at the side of the machine opposite that side shown in Fig. 1;

Fig. 5 is a transverse vertical sectional view taken on line 5—5 of Fig. 2;

20 Fig. 6 is an enlarged longitudinal vertical sectional view taken on line 6—6 of Fig. 2;

Fig. 6^a is an enlarged detailed view of the spreader member to be hereinafter referred to;

25 Fig. 7 is an enlarged fragmentary transverse vertical sectional view taken on line 7—7 of Fig. 2;

Fig. 8 is a fragmentary transverse vertical sectional view taken on line 8—8 of Fig. 1;

30 Fig. 9 is an enlarged transverse vertical sectional view taken on line 9—9 of Fig. 6;

Fig. 10 is a fragmentary longitudinal vertical sectional view taken on the indirect line 10—10 of Fig. 3 and showing the cams for 35 actuating the gripper fingers in the gripper rolls;

Fig. 11 is a bottom plan view of the forming plate and attached tongue;

Fig. 12 is a longitudinal sectional view 40 taken on line 12—12 of Fig. 11;

Fig. 13 is an enlarged top plan view of the parts taken on line 13—13 of Fig. 6;

Fig. 14 is a perspective view of the several rolls of my machine shown in the positions 45 which they occupy when placed in the machine frame, the latter being omitted for the sake of clearness of illustration; said figure also illustrates the manner in which the paper tube is received at the gripper rolls and its 50 several portions gripped by the gripper fingers for forming the diamond fold for the bottom of the bag;

Fig. 14^a is an enlarged view through one side edge of the folded paper tube between 55 the feed and gripper rolls and being taken on line 14^a—14^a of Fig. 14;

Fig. 15 is an enlarged front elevational view of the gripper rolls of my machine, the remaining parts of the latter being omitted 60 for the sake of clearness of illustration;

Fig. 16 is a vertical sectional view taken on line 16—16 of Fig. 15;

Fig. 17 is a vertical sectional view taken on line 17—17 of Fig. 15;

Fig. 18 is a longitudinal sectional view 65 taken on line 18—18 of Fig. 16;

Fig. 19 is a like sectional view taken on line 19—19 of Fig. 17;

Fig. 20 is a like sectional view taken on line 20—20 of Fig. 16;

Fig. 21 is an enlarged fragmentary elevational view, with parts in section, of the gripper fingers in the upper gripper roll, as shown in Fig. 19, and which gripper fingers serve to engage the lip provided on the 75 paper tube in the process of forming the diamond fold for the bottom of the bag; and

Fig. 22 is an enlarged elevational view of one of the gripper fingers and its associated parts, as shown in Fig. 18.

In the drawings, I have illustrated in detail a paper bag making machine constructed in accordance with my invention, and, as shown, the same comprises a supporting frame embracing two longitudinally 85 extending side members 10, 10, laterally spaced apart and maintained in such spaced relation by suitable cross-bars or the like, which may be found most desirable for this purpose. When reference is made herein to 90 the front and rear ends of the machine, the rear end is intended to mean the receiving end of the machine, that is, the end at which the bellows folded tube is fed thereto, and the front end is intended to mean the delivery end of the machine. Secured to and projecting upward from each side member 10 adjacent the rear end of the machine is an upright standard 11, 11, between which extends a cross-bar 12. (See Figs. 1 and 2). 100

Mounted on the latter are two blocks 13, 13, each being provided with an elongated slot 14, through which extends a set screw 15 for adjustably connecting each block with the cross-bar 12 and thereby permit the 105 blocks to be adjusted toward and from each other lengthwise of said cross-bar 12, for the purpose to be hereinafter set forth. Each block 13 is provided in its bottom surface with a groove to receive the cross-bar 110 12, the block having depending flanges at the sides of the groove to prevent the block from being moved transversely of the cross-bar, as clearly shown in Fig. 8. Secured to the upper face of each block 13 is a substantially flat depth plate 16 projecting toward the opposite block and which plates extend into the bellows fold at the sides of the paper tube being operated upon by my machine. By having said blocks 13, 13 adjustable in the manner described, it follows that said depth plates 16, 16 may be adjusted toward and from each other to accommodate them to the depth of the bellows fold in the sides of the paper tube and thus serve to define such depth as the tube is fed to the feed and other rolls of my machine.

Associated with said depth plates 115 120 125

- 16 is a forming plate, which in the instance shown comprises two substantially flat plates 17, 18, maintained vertically spaced apart by an interposed strip or member 19, the latter being of such dimensions as to extend between the plates substantially at or about the center thereof and to occupy the space between the opposed edges of the depth plates 16, 16, as clearly illustrated in Fig. 8.
- 10 The paper tube being fed into the machine completely envelops the forming plates 17, 18, that is, the upper layer of the tube extends over and above the upper plate 17, while the lower layer of the tube extends 15 under and below the lower plate 18, with the depth plates 16, 16 extending inward into the bellows fold at the sides of the tube and thus serving to define the depth of such folds and aid in preventing the tube 20 from being displaced laterally in its movement through the machine.
- Secured to and projecting upward from each frame member 10 at a point forward of the standards 11 is an upright standard 25 20 having a vertical slot therein to receive two bearing boxes 21, 22, in which are journaled the associated ends of shafts 23, 24, upon which are mounted feed or drawing rolls 25, 26, which serve to draw therebetween the folded tube from the forming plates 17, 18. Said rolls 25, 26 are superimposed and have rolling contact with each other, as clearly shown in Figs. 1, 6, 7, and 14. The lower roll 26 is fixed in its position in any suitable manner, but preferably by having its bearing box 22 held against vertical movement in the standards 20. The upper roll 25 is allowed to yield vertically in the standards, and to maintain it properly 30 held against the lower roll, I provide a suitable form of tension device for such purpose, one example of which, as shown in Fig. 1, comprises a spring 27 having a set screw 28 for the purpose of varying the 35 tension of said spring as the case requires. For the purpose of imparting rotary movement to said rolls 25, 26, I provide at one end of the shafts intermeshing gears 29, 30 fixed to said shafts, as clearly shown in Fig. 4.
- 50 Power is transmitted to said feed rolls by having the gear 30 of the lowermost roll meshing with a gear 31, which in turn meshes with a gear 32 secured to the main driven shaft 33 of the machine. For the 55 purpose of transmitting power to said shaft 33, I provide at one end thereof two belt pulleys 34, 35, one being fixed and the other loose, as customary and as shown in Fig. 2. At the opposite end of said shaft 33 I provide a hand wheel 36, which may be used to manually throw over the machine in the initial feeding of the paper tube thereto. The main driven shaft 33 extends transversely across the machine between the side members 10, 10 thereof, and is secured to 65 said members in hangers 37 provided for that purpose.
- The paper tube is fed from the tube forming mechanism (not shown) at the rear of the machine, to the feed rolls 25, 26, and before reaching such parts the tube not only has its side edges given a bellows fold and its longitudinal free edges sealed together by a suitable adhesive, but also has the upper layer or ply of the tube severed or 70 cut by suitable cutting knives or like means to provide a lip or tongue 38 and also two short side cuts 39, 39 at each side but rearward of the lip, as clearly illustrated in Fig. 14. In said figure, I have also shown two 80 transverse cuts 40, 40 extending from the base of the lip toward the side cuts 39 but terminating short of the same, so that there is a portion of the upper layer of the tube left unsevered between the longitudinal cuts 85 39 and the transverse cuts 40. Said transverse cuts 40 extend clear through the tube, that is, through both the upper and lower layers thereof and also through the crease along the inner edge of the bellows fold in 90 each side of the tube, as shown in Fig. 14a. The transverse cuts 40 are formed at the time that the tube is fed or drawn through the feed rolls 25, 26, and to accomplish such result I provide in said rolls suitable cutting 95 mechanism for that purpose. In the form of construction shown in the drawings such cutting means comprise two relatively short cutting knives 41, 41 set in the upper feed roll 25 and arranged so as to extend lengthwise thereof and project radially outward therefrom so as to cut through the tube when passing over the same. Said knives 41 are fixed in such positions and are laterally spaced apart to accomplish the purpose desired. The lower roll 26 is provided in its outer surface with suitable slots or recesses 100 42 to receive said cutting knives when such parts pass each other during the rotation of said rolls.
- Secured to and extending upward from the side members 10, 10 adjacent the front or forward end of the machine, are two upright standards 43, 43, each being provided with a vertical slot of guide-way 44 to receive therein bearing boxes 45, 46 of the two gripper rolls 47, 48, which have rolling contact for the purpose of aiding in feeding the paper tube through the machine. Said boxes 45, 46 are maintained spaced apart 115 by an interposed spacing member in the form of a block 49 located in the slot 44, as shown in Fig. 1. The upper roll 47 is yieldingly held against the lower roll 48 by a spring 50 bearing downward on the box 45 120 and provided with a set screw 51 for the purpose of varying the tension of the spring. Said gripper rolls 47, 48 are provided with

or mounted on shafts 52, 53 journaled at their ends in the associated bearing boxes 45, 46. Said gripper rolls are rotated in the required directions by intermeshing gear wheels 54, 55 mounted on the ends of the shafts 52, 53 at the left-hand side of the machine, as shown in Fig. 4. Power is transmitted to said gear wheels 54, 55 by having the latter intermesh with the gear wheel 31, which in turn meshes with the gear wheel 32 on the main driven shaft 33. Said gripper rolls 47, 48 are provided with suitable gripper mechanism for the purpose of forming the diamond fold at the bottom of each bag, and such mechanism will be presently described.

For the purpose of spreading apart the upper and lower layers of the paper tube as it is fed to the gripper rolls 47, 48 from the feed rolls 25, 26 and to facilitate proper and efficient operation of the gripping mechanism in the former rolls, I interpose between such two sets of rolls a suitable form of spreading mechanism, which in the example shown in the drawings is constructed as follows. Secured to and extending between the side members 10, 10 is a cross-bar 56, the latter being located between the standards 11 and 20, as shown in Figs. 1 and 2. Secured to and extending upward from said cross-bar 56 are two upright standards 56^a, 56^a, of a height substantially equal to that of the standards 56. Said standards 56, 56 are located between the feed and gripper rolls, as shown in Fig. 1. Extending across the machine between the standards 62, 62 and secured to the upper ends thereof is a cross-bar 63. Said guide strips 57, 57 after passing between the feed rolls are secured to the upper face of said cross-bar 63 and extend forward beyond the same to a point short of the gripper rolls 47, 48, as shown in Figs. 1 and 2. Said guide strips are provided with laterally extending portions or ears 64, 64 for this purpose. Between each ear 64 and the cross-bar 63 is a spacing block 64^a to space the guide strip above the cross-bar and permit the folded portions of the paper tube to pass between such parts as is necessary. Secured to the upper surface of said cross-bar 63 is a flat supporting table or plate 65 extending across the space between the guide strips 57 but below the same for the purpose of supporting the lower layer of the paper tube as it is fed from the feed rolls to the gripper rolls. The inner end of said plate 65 terminates short of the feed rolls 25, 26 and is bent or curved downward, as shown in Figs. 1 and 6, for the purpose of allowing the paper tube to enter and slide freely on the upper surface of the plate. Each guide strip 57 at its forward end is bent slightly downward so as to be below the plane of the remaining portion of the strip, as shown in Fig. 6. Secured to the upper surface of each strip at its forward end is a short strip 66 bent slightly upward so as to project above the upper surface of the strip proper and thereby provide at the forward end of each guide strip two vertically separated parts or strips, as shown in Fig. 6. In the space thus provided there operates a movable separator 67 adapted to be reciprocated back and forth into and out of the open end of the slot or space thus formed, by a rod 68. Said spreader 67 is secured to the

rial. Said annular grooves 58, 59 form at each side thereof annular bearing surfaces 60, 61, which have rolling contact with each other, thereby serving to feed the paper tube between the rolls, as is apparent. Secured to each standard 56^a on the top of the portion of the guide strip 57 secured thereto, is a flat plate 56^b, between which and the portion of the guide strip 57 therebelow extends the opposed side end of the associated depth plate 16, as shown in Fig. 1. By such construction, the depth plates 16 are guided by such parts in the adjustment of the depth plates, and further such parts act as stop members to prevent the depth plates from being displaced bodily toward the standards 56^a.

Secured to and projecting upward from the side members 10 are two upright standards 62, 62, of a height substantially equal to that of the standards 56^a. Said standards 62, 62 are located between the feed and gripper rolls, as shown in Fig. 1. Extending across the machine between the standards 62, 62 and secured to the upper ends thereof is a cross-bar 63. Said guide strips 57, 57 after passing between the feed rolls are secured to the upper face of said cross-bar 63 and extend forward beyond the same to a point short of the gripper rolls 47, 48, as shown in Figs. 1 and 2. Said guide strips are provided with laterally extending portions or ears 64, 64 for this purpose. Between each ear 64 and the cross-bar 63 is a spacing block 64^a to space the guide strip above the cross-bar and permit the folded portions of the paper tube to pass between such parts as is necessary. Secured to the upper surface of said cross-bar 63 is a flat supporting table or plate 65 extending across the space between the guide strips 57 but below the same for the purpose of supporting the lower layer of the paper tube as it is fed from the feed rolls to the gripper rolls. The inner end of said plate 65 terminates short of the feed rolls 25, 26 and is bent or curved downward, as shown in Figs. 1 and 6, for the purpose of allowing the paper tube to enter and slide freely on the upper surface of the plate. Each guide strip 57 at its forward end is bent slightly downward so as to be below the plane of the remaining portion of the strip, as shown in Fig. 6. Secured to the upper surface of each strip at its forward end is a short strip 66 bent slightly upward so as to project above the upper surface of the strip proper and thereby provide at the forward end of each guide strip two vertically separated parts or strips, as shown in Fig. 6. In the space thus provided there operates a movable separator 67 adapted to be reciprocated back and forth into and out of the open end of the slot or space thus formed, by a rod 68. Said spreader 67 is secured to the

upper end of said rod 68, the latter being bent inward for that purpose. Said rod 68 is secured at its lower end to a rock shaft 69 extending across and journaled at its ends in the side members 10 of the machine frame. Any suitable form of mechanism may be provided for imparting motion to said rock shaft 69, but, as shown in the drawings, I provide for this purpose a cam 70 mounted on a shaft 71 extending between and having its ends journaled in the side members of the machine frame. Said rock shaft 69 is provided with a cam arm 72 projecting forward therefrom and having at its free or outer end a roller or other bearing member 73 adapted to have rolling contact with the peripheral surface of the cam 70. To hold the roller 73 against the cam 70, I provide a spring 69^a encircling the rock shaft and having one end connected with a fixed lug 69^b on the adjacent side member 10 of the machine frame, and the other end connected with said rock shaft, as shown in Fig. 5. As the cam 70 is revolved it is apparent that the shaft 69 is rocked or oscillated for the purpose of reciprocating the spreaders 67. As illustrated in Figs. 6^a and 13, the spreader 67 is composed of two L-shaped fingers 74, 75 spaced apart vertically at their ends so that when they are projected forward from the space between the spread ends of the guide strips 57 they will serve to separate the upper and lower layers of the tube as it feeds into the gripper rolls 47, 48 and hold such layers in such position so that the gripper fingers in said rolls will be able to readily grip portions of the tube for the purpose which will be presently described. When at rest each spreader 67 lies within the space between the separated ends of the guide strips 57, as shown in Fig. 6, and therefore does not project far enough into the space between the gripper rolls to interfere with the gripper fingers or the cutting knives provided thereon. When the spreader 67 is projected forward, however, it has a throw sufficient to accomplish the purposes desired. To limit the throw of the spreader in both directions, I have provided a guide plate 76 provided with an outwardly opening slot 77, in which the rod 68 has movement, the ends of the slot serving as stop members for the rod, as shown in Fig. 13. As the paper tube is fed from the feed rolls to the gripper rolls, it naturally follows that the sides of the tube formed by the folding thereof pass over the separated forward ends of the guide strips 57, and, inasmuch as the latter are spaced apart vertically as described, they serve to separate the sides of the tube along the line of fold thereof. The upper gripper roll 47 is provided with two annular grooves 78, 78 for the purpose of allowing the spreader 67 to be projected close to

the contacting point of that roll with the lowermost one and thus facilitate allowing the spreader to operate as closely as possible to the rolls.

To facilitate raising the lip 38, I cut both the layers of the paper tube when such portion comes to the proper space between the gripper rolls 47, 48, and thus enable the gripper fingers on the upper gripper 47 to grip the lip and aid in opening the end of the tube for making the diamond fold. To accomplish this, I provide a construction as follows: Extending forward from the center of the forming plates 17, 18 is an extension 79 passing between the feed rolls 25, 26, there being suitable annular grooves 80, 80 provided in the feed rolls for that purpose, as shown in Figs. 2 and 7. Said extension 79 is preferably made of two superimposed strips of metal, an upper strip 81 and a lower strip 82, as shown in Fig. 12. The lower strip 82 terminates short of the forward end of the upper strip 81, but has its forward end bent downward to provide a stop flange 83, as shown in said Fig. 12. Located below the upper strip 81 is a tongue plate 84 having its rear end projecting into the space between the stop flange 83 and the upper strip 81. Said plate 84 is provided at its outer end with a tongue member 85, preferably given the shape as shown in Figs. 11 and 13. Said tongue plate 84 is pivoted intermediate its ends by transverse pivot pins 86, 86 resting in suitable upwardly opening slots or openings provided in the side flanges 87, 87 of the upper strip 81. It will be noted that the pivotal point is nearer the forward end of the tongue plate than its rear end, so that the rear end has a weight greater than the forward end, thereby causing the tongue plate to be acted upon by gravity for the purpose of holding the tongue member 85 normally raised and in position to always bear upward against the under side of the upper layer of the paper tube passing thereover. Said tongue member 85 terminates slightly short of the contacting portions of the two gripper rolls 47, 48, and is normally urged by the action of gravity toward the upper gripper roll. Said tongue 85 is so positioned that the lip 38 in the tube passes over the same as it feeds into the gripper rolls, and by being pivoted in the manner described has a certain amount of flexibility in order to hold the lip 38 against the upper gripper roll so as to be in position to be readily and quickly grasped by the gripper fingers in such roll and furthermore allow it to yield in case any foreign matter should become interposed between the lip and the gripper roll.

The upper gripper roll 47 is provided with two longitudinally aligned fixed cutting knives 88, 88, as shown in Figs. 14 and 15. 130

Said knives project radially beyond the outer surface of the roll and are received in grooves or slots 89, 89 in the lower roll 48 during the rotation of the rolls. Said knives 5 are of such a length and are so positioned that they cut off the tube from the slot 40 (Fig. 14) to the folded side edge thereof. After such operation is effected, the pivoted tongue serves to hold the now free lip 38 10 against the upper roll 47, and the latter is provided with gripper fingers to grip such lip at each side thereof and to carry it upward in the rotation of the roll, the lower layer of the tube being gripped by gripper 15 fingers in the lower roll 48 for the purpose of opening the severed end of the tube in the forming of the diamond fold. In Fig. 14, I have shown such gripper fingers acting to accomplish the function stated, and in 20 Figs. 15 to 22 I have shown the construction of such parts. The gripper fingers for gripping the lip 38 at the sides thereof are located in a suitable chamber or recess 90 opening outward through the cylindrical 25 surface of the upper roll 47 and normally closed by a cover section 91 of the roll 47, as clearly shown in Fig. 19. Projecting inward from said section 91 at or about the center thereof is a supporting plate or member 92. The two gripper fingers 93, 93 are connected at their inner ends with said plate 92 by suitable pivot pins 94, 94. A spring 95 is interposed between and connects said gripper fingers 93 together and 30 serves to draw them toward each other. Said gripper fingers 93 project outward beyond the outer cylindrical surface of the roll 47 through suitable apertures or openings 96 (Fig. 21) provided in the section 35 91 for that purpose. To spread the fingers apart against the tension of the spring 95, I provide an operating rod or bar 97 rockably mounted at its ends in the cover section 91. Pivotaly mounted on said supporting plate 92 between the gripper fingers 40 are two bell crank levers 98, 98, each having one end bearing against the associated inner side edge of the gripper finger 93 and the other end positioned beneath a lug 99 45 secured to said bar 97. At one end of the bar 97 is a spring 100 so formed and connected with the parts that it tends to rock the bar into a position for holding the gripper fingers closed. The other end of the 50 bar 97 projects beyond the end of the roll 47 and has secured thereto an actuating arm 101 having at its free end a suitable roller or member 102 bearing on the outer surface of a fixed cam 103 encircling the shaft 52 at 55 one end of the upper roll 47. The parts are so arranged and timed that the gripper fingers 93 are opened and closed at the proper intervals in the rotation of the rolls 47, 48. From the disclosure made it is clear 60 that when the arm 101 is rocked by the cam 65

103, the gripper fingers 93 will be spread apart in the rocking of the rod 97, due to the fact that the levers 98 are at such time moved outward so as to actuate against the inner sides of the gripper fingers 93 for this purpose. In the opening of the gripper fingers the lip 38 of the paper tube is brought into position to extend across the space between the gripper fingers 93, and as soon as such action takes effect the arm 101 has reached 70 a point allowing the spring 100 to rock the rod 97 for the purpose of bringing the gripper fingers into closed position and gripping the sides of the lip 38 tightly 75 against the roll 47. To accomplish this result, each gripper finger 93 is provided at its outer end with a gripping member 104 having an overhanging portion or tongue 105 adapted to reach over the lip 38 at the side thereof. Said gripping member 104 is 80 secured to the gripper finger 93 by a pivot pin 106 and is provided at its inner end with a lug 107, to which is connected a spring 108, the lower end of the latter being connected with a pin 109 provided on 85 the associated gripper finger 93. The springs 108 serve to normally hold the tongues 105 in open position, but to close them when the gripper fingers are moved toward each other by the spring 100, I provide stop pins 110 on the plate 92 and against which the gripper members 104 are 90 in contact so as to rock the latter about their pivot pins 106 and cause the tongues 105 to be drawn downward toward the roll 100 and against the interposed portion of the paper lip 38 therebetween. From the above it follows that when the rod or shaft 97 is 95 rocked in the opposite direction by the cam, the tongues 105 will be raised from gripping engagement with the interposed paper lip 38 by the action of the springs 108 in the moving away of the gripping members 104 from their stop pins 106 and thereby 105 release the paper lip 38. 110

The upper roll 47 may also be provided with another chamber 111 opening outward through the outer cylindrical surface of the roll and being normally closed by a cover section 112, there being fastening screws 113 provided for that purpose. The chambers 90 and 111 may be made in one, that is, by making the roll 47 hollow as shown in Figs. 16 and 17. Extending inward from said section 112 are two supporting plates 114 having gripper fingers 115 pivoted thereon by pivot pins 116 at the inner ends thereof. Said fingers 115 are drawn toward each other by an interposed spring 117 provided for that purpose. Rockably mounted 120 in said cover section 112 is a rod or shaft 118. For each gripper finger 115 there is a bell crank lever 119, one end of which bears 125 against the inner side edge of the associated gripper finger and the other end of which 130

is depressed by a dog 120 fixed on the rod 118, as clearly shown in Figs. 18 and 22. From this it follows that when the rod 118 is rocked, the dogs 120 are moved downward against the bell crank levers 119, and the latter serve to move the gripper fingers 115 away from each other against the tension of the spring 117, the latter serving to hold the gripper fingers in contact with the bell crank levers. Each gripper finger 115 projects outward through the cover section 112 through a suitable opening or slot 121 provided for that purpose, said slots being elongated so as to permit the swinging movement of the gripper fingers 115. The rod 118 is also provided adjacent each gripper finger with a gripper dog 122 rigidly secured to the rod and adapted in the rocking thereof to be moved toward and from the outer end of the gripper finger 115. Each gripper finger 115 is provided at the outer end thereof with a fixed overhanging gripping flange 123, toward which the gripper dog 122 moves. At one end of said rod 118 is a coiled spring 124, serving to close the gripper fingers. To rock the shaft or rod 118 in the opposite direction, that is, to open the gripper fingers to receive therebetween the portion of the paper tube to be gripped by such parts, I provide at the opposite end of said rod an arm 125 having at its free end a roller 126 bearing on a fixed cam 127 encircling the shaft 52 of the upper roll 47. It will be noted from an inspection of Fig. 15 that the cam actuating mechanism for the rod 118 is at that end of the roll 47 opposite to the cam operating mechanism of the rod 97 for the gripper fingers for the paper tongue 38, although any other arrangement of the parts may be made to meet the requirements of the particular machine being made. The gripper fingers 115 and the associated dogs 122 are so positioned in the roll 47 as to grip when closed the upper layer of the paper tube as it is brought around the upper roll 47, as shown in Fig. 14. It will be noted that said gripper fingers 115 and 122 grip the paper tube over the outer creased edge of the upper layer, and the action thereof is positive. In other words, such gripper parts are moved apart from each other to permit the edges of the tube to be fed into position so that the gripper flange 123 is brought inward against the outermost part of the paper tube, while the gripper dog 122 is moved outward to engage the innermost part of the paper tube, thereby causing such gripper parts to firmly grip the paper tube between them. The action of such parts is very rapid in the operation of the machine, and to prevent breaking of the coacting parts of such gripper mechanism as they are brought toward each other, I provide means for preventing such parts from pounding against each other when the machine is run without any paper stock therein. If such means were not provided, it is apparent that the flange 123 of each gripper finger 115 would be crystallized by the pounding thereagainst of the associated gripper dog 122. To overcome this, I provide on the rod 118 a suitable stop member 128, which serves to limit the rocking movement of the rod at a point to prevent the dog 122 from coming into actual contact with the gripper flange 123 at all times.

The upper roll 47 is also provided with two short creaser blades 129, there being suitable grooves or slots 130 in the lower roll 48 to receive them as such parts come opposite each other in the rotation of the rolls. Said creaser blades 129 serve to crease the tube from its folded side edges inward a short distance for the purpose of defining the diamond fold and prevent the tube from buckling or folding upon itself at any other point as the diamond fold is formed and carried downward from the top gripper roll.

The lower roll 48 is also provided with a set of gripper fingers 131, 131 and coacting gripper dogs 132, 132 located in suitable slots 133 provided in the removable section 134 of said lower roll. Such parts are made like and operate in the same manner as the sets of gripper fingers 115 and gripper dogs 122 previously described and clearly shown in Figs. 18 and 22, respectively. These gripper fingers serve to grip the lower layer of the paper tube as it is operated upon by the gripper rolls and serve to spread open the portion of the paper tube in the making of the diamond fold for the bottom of the bag, as shown in Fig. 14. The lower roll 48 is also provided with a cutting knife 135, as shown in Fig. 20. Said knife 135 is secured to the inner end of an operating arm 136 pivoted at 137 to a removable section 138 of the roll 48. The outer end of said arm 136 projects beyond the adjacent end of the roll and is provided at that end with an enlarged portion 139 adapted to be operated upon by a fixed cam arm 140, as shown in Fig. 15. The rod 136 is moved against the tension of a spring 141. The rod and knife are located in an outwardly opening slot 142, and when the rod is operated by the cam the knife is moved outward through the slot and serves to cut off the uncut part of the central portion of the lower layer of the tube from the previous bag section having already passed through the rolls 47, 48 in the forming of the diamond fold for the bottom thereof. Said cutter 135 is moved into and out of a suitable slot or groove in a roller 143 provided at the front of the machine and in rolling contact with the lower roll 48. The latter is mounted on a suitable shaft 144 having its 130

ends journaled in brackets 145 secured to the upright standards 43 by fastening screws 146, as shown in Fig. 1. Said brackets 145, 146 are yieldingly held against the standards 43, 43 by springs 146^a encircling said screws 146 and being interposed between the heads thereof and the brackets 145.

Located in front of the gripper rolls 47, 48 are two spreading members or arms 147, 147, the latter depending downward from a cross-bar 148 extending across the front of the machine and secured to the upright standards 43. Said arms 147 are pivoted at their upper ends on pivot pins 149, and one 15 has a notch 150, into which extends a lug 151 on the other, so that the movement of one will effect the movement of the other for the purpose of throwing the lower ends of the spreaders apart to aid in breaking the 20 inside folds of the portion of the tube to be converted into a diamond fold. In Fig. 3 the arms are shown in closed position or inactive, while in Fig. 14 said arms are shown 25 swung into their open position. Said spreaders 147 are operated automatically and at the proper time for the purpose stated, and to accomplish this I extend the upper end of one of the spreaders above its 30 pivot 149 and connect such end with an endwise movable rod 152 by a pivot pin 153, as clearly shown in Fig. 5. The outer end of said rod slides through a suitable bracket or hanger 154, between the depending arms of which is a spring 155. Said spring encircles 35 said rod and has one end connected therewith so as to normally throw the rod into a position holding the spreaders closed, as shown in Fig. 3. To push said rod 152 in the opposite direction, I provide a suitable 40 type of mechanism, which comprises a bell crank lever 156 connected by a vertical pivot pin 157 to a cross-bar 158 extending transversely of the machine between the upright standards 43. Said lever 156 has the 45 end 159 thereof extending downward at the inner side of the cross-bar, and is in a position to operate against the adjacent end of the rod 152 when the bell crank lever is moved for that purpose. Connected with 50 the other end of said lever 156 is an operating rod 160, the latter being connected at its rearward end by a pivot pin 161 with a vertically arranged arm 162, which in turn is pivotally mounted at its lower end on a stud 55 163 secured to and projecting inward from one of the side members 10 of the machine frame (Fig. 6). Encircling such stud is a spiral spring 164, one end of which is connected with the stud and the other end connected with the rod 162 so as to hold the 60 roller 165 thereon against the peripheral surface of a cam 166 fixed to the shaft 24 of the lowermost feed roll 26, as clearly shown in Figs. 6 and 7. As illustrated, said

cam 166 is provided at one place on its peripheral surface with a radial cam projection 167, which when operating against the roller 165 serves to throw the rod 162 and its connected parts forward for the purpose of opening the spreaders 147. The action of 70 the spreaders is very rapid, being opened and closed intermittently at the speed required to accomplish the function heretofore stated.

Also located at the front of the machine 75 adjacent the combined gripper and feeding rolls 47, 48 is a pair of ironers, preferably comprising two relatively flat plates 168, 168. Each plate 168 is secured to a vertically arranged rock shaft 169 having its 80 lower end stepped and journaled in a vertical bracket 170 depending from the cross-bar 158. Said shafts 169 have their upper ends extending through and journaled in said cross-bar, and each is provided with a 85 rigid arm 171, the latter being connected at their ends by a link 172, as shown in Figs. 2 and 3, so that both of the ironer plates may be operated in unison. One of said rock shafts 169 is also provided at its upper end 90 with a rigid arm 173, to the outer end of which is pivotally connected a rod 174, the latter having its inner end connected by a pivot pin 175 with an arm 176, the latter extending downward immediately beyond the 95 feed rolls 25, 26, as shown in Fig. 6. The lower end of said arm is pivoted to a stud 177 rigidly secured to and projecting inward from the same side member 10 of the machine frame as the stud 163. Encircling 100 said stud 177 is a spiral spring 178 having one end connected with the stud and the other end connected with said arm, so that the spring will normally tend to maintain the arm 176 in a position to hold the ironer 105 plates closed. Said arm 176 is rocked in the opposite direction and against the tension of its spring by a cam 179 also on the shaft 24 of the lower feed roll and operating against a roller 180 on said arm, as shown 110 in Fig. 6. By the construction described, it naturally follows that the ironer plates 168 will be opened and closed through the intermediary of the revolving cam 179 and when closed will occupy the positions shown 115 in Fig. 3. The ironer plates are opened simultaneously to permit the tube to be fed through the combined feed and gripper rolls 47, 48, and then the spreading arms 147 are rapidly moved apart for the purpose of aiding in breaking the crease or fold at the sides of the tube and are immediately returned to closed position after accomplishing that function. When this has been performed, the ironer plates 168 are immediately moved into closed position and serve 120 to fold the open end of the tube against the gripper rolls 47, 48, as shown in Fig. 14.

In preparing the machine for work, the machine is turned over manually for the purpose of feeding the paper tube thereinto, and to permit the operator to gain access to the feed rolls at the front of the machine, I have provided a mechanism whereby the spreader arms 147 and the ironer plates 168 may be manually operated in order to be swung bodily outward from the gripper rolls and thus permit this access to be had. Such mechanism is constructed as follows. Extending between the side members 10 of the machine frame is a rock shaft 181 (Fig. 6), one end of which extends beyond one of the side members 10 and has secured thereto an operating handle or lever 182 so that the operator may grasp the same in manually moving the spreaders and ironer plates to a position to permit access to be had to the portion of the feed rolls therebehind. Rigidly secured to said rock shaft 181 is an arm 183, to which is connected a rod 184 by a pivot pin 185. The opposite end of said rod 184 extends to the arm 176, which forms part of the mechanism for automatically opening and closing the ironer plates, as shown in Fig. 6. Said rod 184 is connected to said arm 176 by a pin 186 extending through an elongated slot 187 in said rod 184. Said slot 187 is elongated lengthwise of the rod so as to provide for lost motion between the parts and thus permit the arm 176 to be rocked back and forth by its cam without in any manner serving to move the rod 184. Such motion is toward and from the forward end of the slot 187 so that when the rod 184 is moved endwise by the hand lever 182, it follows that the arm 176 will be moved for the purpose of opening the ironer plates. Rigidly secured to said rock shaft 181 is an arm 188, to which is connected a rod 189 by a pivot pin 190. Said rod 189 extends upward, as shown in Fig. 6, and has its upper end connected by a pin 191 and an elongated slot 192 with a hand lever 193. Said lever 193 is preferably located adjacent the top of one of the upright standards 43 and on the same side of the machine as the hand lever 182, heretofore referred to, so that both of such parts are accessible from the same side of the machine. The cross-bar 148 is provided with two upwardly projecting lugs 195 spaced apart endwise of the bar, as shown in Fig. 2. Located between said lugs and rockably mounted therein is a plate 196, to the outer edge of which is pivotally connected the spreader arms 147, so that when the plate is rocked upward the spreader arms will be swung bodily outward from the gripper rolls 47, 48, independently of the ironer plates 168, as is apparent. Said plate 196 has one end projecting beyond the innermost lug 195 and about which is encircled a spring 197, one

end being connected with the lug and the other end with the cross-bar 148, so that said spring normally serves to maintain the plate 196 lying flatwise against said cross-bar and thus hold the spreader arms 147 in their operative position, namely, closely adjacent the gripper rolls 47, 48, as shown in the drawings. The opposite end of said plate 196 extends beyond the outermost lug 195 and has rigidly connected therewith the adjacent end of the hand lever 193, as shown in Figs. 2 and 6. As illustrated in the latter figure, the slot 192 is elongated lengthwise of the rod 189 and the pin 191 normally lies at the upper end of said slot so that when the hand lever 193 is grasped and moved downward the plate 196 will be rocked upward for the purposes stated, independent of any movement being imparted to the rod 189 and consequently independent of any movement being imparted to the ironer plates. But when the rod 189 is moved downward by actuating the hand lever 182, it follows that the plate 196 and its attached spreader arms 147 will be swung bodily outward away from the gripper rolls simultaneously with the movement given to the ironer plates to open the same.

After the diamond fold has been completed and after the tube has been completely severed by the cutter 135 in the roll 48 the gripper fingers in the gripper rolls are actuated so as to release their hold on the paper tube and thereupon permit the machine to feed the paper tube downward between the lower gripper roll 48 and the roll 143. From such set of rolls the tube with its diamond fold is fed to a set of rolls therebelow, one of such rolls constituting a paste roll and provided with parts for applying paste to the marginal edges of the folded portions of the diamond fold so that such portions when ultimately folded will be sealed together to complete the bottom of the bag being formed when fed forward to the folding rolls utilized for that purpose and not shown in the drawings as being old in the art. To prevent the paper tube from adhering to and being carried around with the lower gripper roll 48 after the gripper fingers therein have released themselves from engagement with the tube, I provide a number of guide members 198, which may take the form of wires or other metal strips. Said guide wires 198 have their upper ends extending partially into the annular grooves 199 provided for that purpose in the lower gripper roll 48, as shown in Fig. 6. In the machine illustrated, there are two of such wires. Said wires 198 are anchored in a cross-bar 200 extending across the front of the machine and suitably secured to the rigid frame thereof. For the purpose of guiding the folded portion of the bag forming the dia-

mond fold straight downward from the lower gripper roll 48 to the paste roll 201, located therebelow, I provide a number of guide members 202 preferably in the form of wires or other metallic strips, as found most desirable. Said wires 202, as shown in Fig. 6, have their outer ends secured or anchored to a cross-bar 203, which is located in front of the roll 143, and is suitably secured to the brackets or boxes 145, in which the shaft of the roll 143 is journaled. Said wires 202 extend inward over the top of said roll 143 and downward toward the paste roll, as shown in Fig. 6, there being a suitable space provided between said wires 202 and 198, as shown in Fig. 6, so as to provide a channel for the reception of the paper tube as it is fed toward the paste roll. The roll 143 is provided with suitable annular grooves 204, in which the wires 202 lie. As shown in Fig. 3, the paste roll 201 is provided with paste applying ribs 205. Located to the rear of said paste roll 201 and having rolling contact therewith are two idler rolls 206, 207, one being located above the other, as shown in Figs. 6 and 14, and serving to hold the interposed paper tube against the paste roll and permit it to be fed beyond the same for the purpose of having the diamond fold operated upon further in the folding of the diamond fold to complete the bottom of the bag. The wires 198 extend downward between the paste roll 201 and the uppermost idler roll 206 and also between the paste roll and the lowermost idler roll 207, said idler rolls being provided with annular grooves 208, 209 for that purpose. Located below the paste roll is a feed roll 210, and between said rolls the wires 198 extend, as shown in Figs. 3 and 6. The portion of each wire 198 to the rear of the paste roll 201 and between the idler rolls 206, 207 is looped rearward and held in position by suitable wires or members 211, the latter being anchored in a cross-bar 212. To further aid in guiding the paper tube as it passes between and from the paste roll 201 and the lowermost feed roll 210, I also provide suitable guide wires or like members 213 preferably having their inner ends anchored to the cross-bar 212 and passing between the paste roll and the feed roll therebelow. The latter is provided with a plurality of annular grooves 214 to receive all of said wires, as shown in Figs. 3 and 6. The bottom of the guide channel for the paper tube as it is fed from the paste roll 201 onward to the folding rolls (not shown) is formed by the wires 198 and 213. The top of said channel is formed by guide wires 214^a, 214^b anchored in a cross-bar 214^b extending across the front of the machine in front of the paste and feed rolls 201, 210, respectively. There are two of such wires 214^a, one above each wire 213, as shown in

Fig. 3, and the inner end of each wire 214^a extends into an annular groove 214^c provided in the paste roll 201 so as to prevent the paper tube from following the paste roll and further to strip the tube from said paste roll in case the tube should become adhered thereto by the paste applied to the tube. 70

The feed roll 210 is mounted on the shaft 71 and the latter has its ends journaled in suitable bearing boxes 215 retained in vertical slots 216 in upright standards 217, as shown in Figs. 1 and 4. At the left-hand side of the machine the shaft 71 is provided with a gear wheel 218, as shown in Fig. 4, meshing with a gear wheel 219, the latter meshing with a gear wheel 220, which in turn meshes with the large intermediate gear 31, as shown in said Fig. 4. By the arrangement of the gearing illustrated, it follows that power is transmitted from the main driven shaft 33 to the shaft 71 through the intermediary of the train of gearing referred to. Said shaft 71 is also provided with a gear wheel 221, which meshes with a gear wheel 222 on the shaft 223, upon which the paste roll 201 is mounted. From this it follows that the paste roll is rotated from the shaft 71 by the gear just referred to. 85

The shaft 144 is provided at the left-hand side of the machine with a gear wheel 224, which meshes with the gear wheel 55, as shown in Fig. 4, so that power may be transmitted to said shaft from the main driven shaft 33. As shown in Fig. 1, the shaft 223, 100 upon which the paste roll is mounted, has its ends journaled in suitable bearing boxes 225 suitably mounted in the upright standard 217. Said roll 201 is yieldably held in position by springs 226, the tension of which may be adjusted by set screws 227 in the usual manner. The boxes 215 and 225 may be separated by an interposed separating member 228. 105

The ends of the shafts 231 and 231^a, upon which the idler rolls 206, 207 are mounted, are yieldably supported in suitable brackets or boxes 229, 230, as shown in Fig. 10. The shaft 231 of the upper idler roll 206 is journaled in a box 232, which is slidably mounted in said bracket 229, there being a spring 233 interposed between the box and the opposed rigid part of the bracket, so that the idler roll may be held yieldingly against the paste roll 201. The same construction is provided for the lower idler roll 207, and like parts have been indicated by like reference numerals. 115

The shafts 231 and 231^a are each provided with a gear wheel 231^b and 231^c, respectively, and which gear wheels mesh with the gear wheel 222 as shown in Fig. 5. 125

In order to make room for the paste pan or dish (not shown) at a point in front of the paste roll 201, I secure the standards 217 13

of the paste roll to an inclined step or surface 234 on the side member of the machine frame at the front thereof, as shown in Fig. 1.

5 By providing the cutter knives 41, 41 in the feed rolls 25, 26 instead of placing them in the gripper rolls 47, 48, I am enabled to provide the proper amount of space on the gripper rolls for the guide wires 198, 198 to be associated therewith, for if said knives were in the gripper rolls it would naturally follow that they would occupy that space into which the guide wires 198 now extend. By providing the set of cutting knives 88 and 135 in the two gripper rolls 47, 48, I am enabled to accomplish the results to be performed by said knives in the gripper rolls themselves and thereby aid in shortening the length of the complete machine, instead of being required to employ such set of knives in another set of rolls or other parts that would be independent of the gripper rolls. It naturally follows that there is not only a saving in material used 20 in constructing the complete machine, but also a reduction in labor cost, as well as floor space required to be occupied by the machine. These are all essential advantages in constructing and operating machines of this 25 character. It will be noted that the paste roll 201 is located directly below the gripper rolls and therefore in a position not only to effectively accomplish the purpose for which it is designed, but is located in a 30 position that aids in shortening the ultimate length of the machine.

Briefly, the machine described and shown herein operates in the following manner. The paper stock from which the bag is made 35 is fed from a roll of such stock mounted beyond the rear end of the machine. The paper sheet is initially of a width equal to the width of the bag when completely opened and spread out flat, and, on being drawn 40 from the roll of paper, is operated upon by suitable folding devices for folding the paper sheet in the form of a tube and providing the bellows fold in the side thereof, and also has the longitudinal meeting edges 45 of the folded tube sealed together by an adhesive applied to the tube as it is advanced to the machine. Before the paper tube reaches the feed rolls 25, 26, the upper layer thereof is cut to form the longitudinal 50 or side cuts 39, 39 and the lip 38. Such parts of the complete machine are not shown in the drawings because they are old and well known in the art, but of course will be used in connection with the machine 55 herein described and shown in order to complete the tube before being operated upon by the mechanism which I have heretofore described and as constituting the subject-matter of my present invention. After the 60 tube has been formed and operated upon to the extent noted, the same is fed to the feed rolls 25, 26, whereupon the knife blades 41, 41 cut the transverse slots 40, 40 in the tube to the extent shown in Fig. 14. The tube is then guided by the guide strips 57, 70 75 to the gripper rolls 47, 48, and just prior to being engaged by said gripper rolls the sides of the tube are spread apart by the spreading devices heretofore described, and also fed to the rolls by the reciprocating spreaders 67. Both layers of the tube are then severed from the base of the lip 38 outward through the bellows fold at the sides thereof by the cutting knives 88, 88 in the upper gripper roll 47, whereupon the upper 80 layer of the tube is free to be raised toward the upper gripper roll, and the yieldable tongue 85 serves to hold the lip 38 against the upper gripper roll, to be engaged by the gripper fingers 93, 93, while the side edges 85 of the upper layer are also gripped at the proper time by the other gripper fingers 115, 115, while the separated lower layer of the tube is gripped at its sides by the lower gripper fingers 131, 132. The mouth 90 of the tube is then opened and projects forward from the gripper rolls 47, 48, whereupon the spreader arms 147, 147 are actuated to break the folds at the sides of the tube, whereupon the ironer plates 168, 168 95 are closed and serve to flatten out the outwardly projecting portions of the tube against the gripper rolls, as shown in Fig. 14. The reciprocating knife 135 in the lower gripper roll 48 is actuated at the 100 proper time to sever the now folded end of the tube from the portion of the tube preceding it, and thereupon the several sets of gripper fingers are released from their engagement with the folded end of the tube 105 at the gripper rolls to permit the tube to be fed downward past and beyond the paste roll 201. From such roll the folded tube is acted upon by suitable folding rolls situated beyond the forward end of the machine 110 parts shown, in order to fold the thus made diamond fold into the position required to completely form the bottom of the bag. These parts are not shown in the drawings as they are well known in the art and will 115 of course be utilized with the part of the complete machine heretofore described.

Among the advantages of my novel construction are the following: The parts are so constructed that they are durable, and 120 are so arranged that the machine is compact and thereby shortens up the length of the machine and permits it to occupy a smaller amount of floor space than required for machines of the type heretofore constructed. Furthermore, my machine is a high speed 125 one, and permits the making and turning out of complete bags in great numbers and in a short period of time. The guide strips 57 serve to properly guide the tube through the 130

machine and thus prevent the tube from lateral as well as vertical displacement, so that the diamond fold may be properly and efficiently made in the rapid operation of 5 the machine, with the attendant result of forming perfect bags and overcoming waste. This is a decided advantage in machines of this character, because in being run at such high rates of speed, the operator is unable 10 to detect an imperfect bag the instant it is made but must wait until it has been completely formed and discharged before noting the imperfection, and at such time there are a number of such bags still in the machine, 15 with the result of waste being self evident. Then again, the action of the gripper fingers is positive and grips the parts of the tube at the sides instead of at the ends, with the result that the paper tube is not unnecessarily drawn or distorted in the gripping 20 operation. Moreover, the paste roll is located in such a position that the paste dish may be readily reached by an operator for refilling, cleaning, and repair without being required to disassemble or displace any of the 25 parts of the machine for that purpose. Then again, the guide wires by having their ends projecting into annular grooves in the associated rolls, the paper tube is stripped from 30 the rolls and prevented from following the same in case the tube should become adhered to the rolls by paste clinging to the portions of the tube not required to be pasted, and also to actuate and efficiently guide the tube 35 in its path through the rolls so as to prevent the tube from becoming laterally displaced in its travel through the machine and thus enable the formation of perfect bags at all times. A further advantage of my device 40 resides in the fact that the spreader arms 147 and the ironer plates 168 may be manually thrown bodily away from in front of the gripper rolls to permit the operator to have access to the portion of the gripper 45 rolls behind such parts when it is desired to feed the stock in the first instance into the machine. Moreover, by the guide strips 57, the stock may be fed properly to the gripper rolls from the feed rolls in the initial starting of the machine, as such parts are readily 50 accessible from the top of the machine and not in any way interfered with by other mechanism. Then again, the train of gearing is all on one side of the machine, which 55 of course facilitates adjustment and repair. Other and further advantages of my improved device will be readily apparent to those skilled in the art to which my invention relates. 60 While I have shown and described in detail herein a bag making machine embodying the features of my invention, yet it is of course to be understood that the various details of construction and arrangement of 65 parts shown may be variously modified and

changed without departing from the spirit and scope of my invention, and I do not wish to be limited to the details of construction and arrangement of parts shown except as pointed out in the annexed claims. 70

I claim as my invention:

1. In a machine of the character described, the combination with a set of gripper rolls and a set of feed rolls, the latter being adapted to feed a bellows folded tube toward 75 said gripper rolls, of guide strips adapted to project into the bellows fold at the sides of the tube and extending between said two sets of rolls, said strips extending between and to the rear of said feed rolls, 80 the latter being provided with annular grooves to receive said strips, and means for supporting said guide strips in position.

2. In a machine of the character described, the combination with a set of gripper rolls 85 and a set of feed rolls, the latter being adapted to feed a bellows folded tube toward said gripper rolls, of guide strips adapted to project into the bellows fold at the sides of the tube and extending from a point in 90 the rear of and through said feed rolls and having their forward ends terminating short of said gripper rolls, and two sets of standards for supporting said guide strips in position and having connection therewith, one 95 set of said standards being located adjacent the rear ends of said guide strips and the other set being located adjacent the forward ends of said strips.

3. In a machine of the character described, 100 the combination with a set of gripper rolls and a set of feed rolls, the latter being adapted to feed a bellows folded tube toward said gripper rolls, of means for guiding the folded tube from the feed to the gripper 105 rolls, depth plates located to the rear of said feed rolls and adapted to project into the bellows fold at the sides of the tube, and supporting means for said depth plates.

4. In a machine of the character described, 110 the combination with a set of gripper rolls and a set of feed rolls, the latter being adapted to feed a bellows folded tube toward said gripper rolls, of means for guiding the folded tube from the feed to the gripper 115 rolls, depth plates adapted to project into the bellows fold at the sides of the tube, and means adjustably connecting said plates with the frame of the machine so that said plates may be adjusted toward and from 120 each other.

5. In a machine of the character described, the combination with a set of gripper rolls and a set of feed rolls, the latter being adapted to feed a bellows folded tube toward 125 said gripper rolls, of means for guiding the folded tube from said feed to said gripper rolls, depth plates adapted to project into the bellows fold at the sides of the tube, a cross-bar secured to the machine frame and 130

- extending across the same beneath said depth plates, a block secured to each depth plate, and means for adjustably connecting each block with said cross-bar, comprising 5 a fixed member in one of said parts and an elongated slot in the other of said parts.
6. In a machine of the character described, the combination with a set of gripper rolls and a set of feed rolls, the latter being 10 adapted to feed a bellows folded tube toward said gripper rolls, of depth plates adapted to project into the bellows fold at the sides of the tube and being located rearward of said feed rolls, means for adjustably connecting said plates with the frame of the machine so that said plates may be adjusted toward and from each other, and guide strips adapted to project into the bellows fold at the sides of the tube and extending 15 between said depth plates and said gripper rolls.
7. In a machine of the character described, the combination with a set of gripper rolls and a set of feed rolls, the latter being 20 adapted to feed a bellows folded tube toward said gripper rolls, of guide strips adapted to project into the bellows fold at the sides of the tube and extending between said feed and gripper rolls, and said guide strips 25 being provided at their ends adjacent said gripper rolls with means for separating the upper and lower layers of the tube as it is fed to said gripper rolls.
8. In a machine of the character described, 30 the combination with a set of gripper rolls, of means for feeding a bellows folded tube thereto, guide strips adapted to project into the bellows fold at the sides of the tube and terminating short of said gripper rolls, spreading members adapted to be moved 35 back and forth beyond the ends of said guide strips, and means for actuating said spreading members.
9. In a machine of the character described, 40 the combination with a set of gripper rolls, of means for feeding a bellows folded tube thereto, guide strips adapted to project into the bellows fold at the sides of the tube and terminating short of said gripper rolls, a 45 spreading member at the end of each guide strip and comprising two parts vertically spaced apart and adapted to be reciprocated toward said gripper rolls, and means for actuating said spreading members.
- 50 10. In a machine of the character described, the combination with a set of gripper rolls, of means for feeding a bellows folded tube thereto, guide strips adapted to project into the bellows fold at the sides 55 of the tube and terminating short of said gripper rolls, said strips being provided at their ends adjacent said rolls with vertically separated parts adapted to separate the upper and lower layers of said tube as it is fed to said rolls, and a spreading member 60
- associated with each guide strip and adapted to be reciprocated into and out of the space between the separated parts thereof.
11. In a machine of the character described, the combination with a set of gripper rolls, of means for feeding a bellows folded tube thereto, guide strips adapted to project into the bellows fold at the sides of the tube and terminating short of the gripper rolls, a spreading member for each guide strip and adapted to be reciprocated back and forth beyond the end thereof toward said gripper rolls, and means for actuating said spreading members, including a rock shaft. 70
12. In a machine of the character described, the combination with a set of gripper rolls, of means for feeding a bellows folded tube toward said gripper rolls, guide strips adapted to project into the bellows fold at the sides of the tube and terminating short of said gripper rolls, a spreading member at such end of each guide strip and adapted to be reciprocated back and forth beyond the ends thereof, and means for actuating said spreading members, including a rock shaft, means for operating said rock shaft, and a rod connecting each spreading member with said rock shaft. 80
13. In a machine of the character described, the combination with a set of gripper rolls, of means for feeding a folded tube thereto after the upper layer of said tube has been cut to provide a lip therein, a tongue plate located adjacent said gripper rolls and adapted to raise said lip toward the upper gripper roll, and a supporting means for said tongue plate, the latter being pivoted intermediate its ends to said supporting means; the pivotal connection of said tongue plate 90 with said supporting means being nearer the forward end of said tongue plate than the rear end thereof. 95
14. In a machine of the character described, the combination with two gripper rolls, one above the other, of means for feeding a folded tube thereto, a forming plate to the rear of said gripper rolls and provided with an extension extending toward said gripper rolls and terminating short thereof, a tongue plate pivotally mounted on said extension adjacent the forward end thereof and projecting forward therebeyond and into the space between said gripper rolls and adapted to bear upward 110 against the upper surface of the folded tube; the pivotal connection of said tongue plate with said extension being nearer the forward end of said tongue plate than its rearward end so that the weight of the latter will be 115 greater than the weight of the former, and said extension being provided with a stop member below the rearward end of said tongue plate. 120
15. In a machine of the character de- 130

scribed, the combination with a set of gripper rolls and means for feeding a folded tube thereto, of two ironer plates located in front of said gripper rolls, means for swinging said ironer plates into and out of their opened and closed positions during the operation of the machine, and manually operated means connected with said ironer plates whereby the latter may be swung into and out of their opened and closed positions independently of said first named means.

16. In a machine of the character described, the combination with a set of gripper rolls and means for feeding a folded tube thereto, of two ironer plates located in front of said gripper rolls, a rock shaft, a hand lever connected with said rock shaft, and means connecting said rock shaft with said ironer plates whereby the latter will be swung into and out of their opened and closed positions upon the movement of said hand lever.

17. In a machine of the character described, the combination with two gripper rolls, one above the other, and means for feeding a folded tube to said gripper rolls, of a cross-bar extending across the machine adjacent the upper gripper roll, two brackets secured to and depending from said cross-bar, two shafts depending from said cross-bar, an ironer plate secured to each shaft, and the latter journaled at one end in said bracket and the other in said cross-bar, an arm secured to each of said shafts, a link connecting said arms together so that said shafts may be rocked simultaneously, and mechanism connected with one of said shafts for imparting rocking motion thereto during the operation of the machine.

40 18. In a machine of the character described, the combination with two gripper rolls, one above the other, and means for feeding a folded tube to said gripper rolls, of a cross-bar extending across the machine adjacent the upper gripper roll, two brackets secured to and depending from said cross-bar, two shafts depending from said cross-bar, an ironer plate secured to each shaft, the latter journaled at one end in said bracket and at the other end in said cross-bar, an arm secured to each of said shafts, a link connecting said arms together so that said shafts may be rocked simultaneously, one of said shafts being provided with a second arm, a rod pivotally connected at one end with said second arm, an actuating arm depending from said first rod and having pivotal connection therewith, a stud, said actuating arm having pivotal connection with said stud, a spring having one end connected with said stud and the other end connected with said actuating arm so as to normally urge said arm in one direction, a cam, a roller on said actuating arm bearing

against said cam, and means for rotating 65 said cam.

19. In a machine of the character described, the combination with two gripper rolls, one above the other, and means for feeding a folded tube to said gripper rolls, 70 of a cross-bar extending across the machine adjacent the upper gripper roll, two brackets secured to and depending from said cross-bar in front of said gripper rolls, two shafts extending from said cross-bar, one for each 75 bracket and journaled at one end in said bracket and at the other end in said cross-bar, two ironer plates, one connected with each of said shafts, an arm secured to each of said shafts, a link connecting said arms 80 together so that said shafts may be rocked simultaneously, one of said shafts being provided with a second arm, a rod pivotally connected with said second arm, an actuating arm depending from said rod and having pivotal connection therewith, a fixed stud, said actuating arm having pivotal connection with said stud, a spring having one end connected with said stud and the other end connected with said actuating arm, a 90 cam acting against said actuating arm for moving the same against the tension of said spring, a rock shaft, a hand lever secured to said rock shaft, a fixed arm on said rock shaft, and a rod pivoted to said fixed arm 95 and the other end of said rod being connected with said actuating arm by a pin and slot.

20. In a machine of the character described, the combination with two gripper rolls, one above the other, of feed rolls serving to feed a folded tube to said gripper rolls, a cross-bar extending across the machine adjacent said upper gripper roll, two brackets secured to and depending from said cross-bar in front of said gripper rolls, two 105 shafts depending from said cross-bar, one for each bracket and journaled at one end in said bracket and at the other in said cross-bar, two ironer plates, one secured to each of said shafts, an arm secured to each of said shafts, a link connecting said arms together so that said shafts may be rocked simultaneously, a second arm secured to one of said shafts, a rod having pivotal connection with said second arm, an actuating arm depending from said rod and having pivotal connection therewith, a fixed stud, said actuating arm being pivotally connected with said stud, a spring, one end being connected with said stud and the other end with said actuating arm, and a cam connected with one of 110 said feed rolls and adapted to move said actuating arm against the tension of said spring.

21. In a machine of the character described, the combination with two gripper rolls, one above the other, and means for feeding a folded tube thereto, of a cross-bar

extending across the machine above the upper gripper roll, two spreader arms depending from said cross-bar and being pivotally connected adjacent their upper ends thereto, 5 said arms being provided with coacting parts adapted to effect the movement of both of said arms when movement is imparted to one of the same, an endwise movable rod connected with one of said arms, a spring for 10 moving said rod in one direction, a pivotally mounted bell crank lever adapted to move said rod in the opposite direction, a second rod connected with said bell crank lever, an actuating arm connected with said second 15 rod, a fixed stud, said actuating arm having pivotal connection with said stud, a spring connected at one end with said stud and at the other end with said actuating arm, and a rotatable cam operating against said actuating arm.

22. In a machine of the character described, the combination with two gripper rolls, one above the other, of two feed rolls for feeding a folded tube toward said gripper rolls, a cross-bar extending across the front of the machine adjacent the upper gripper roll, two spreader arms depending from said cross-bar in front of said gripper rolls and having pivotal connection at their 25 upper ends with said cross-bar, said arms being provided with coacting parts adapted to effect the movement of said arms toward and from each other when one of said arms is moved, an endwise movable rod connected 30 with one of said arms, a spring for moving said rod in one direction, a pivotally mounted bell crank lever adapted to move said rod in the opposite direction, a rod connected with said bell crank lever, an actuating arm 35 connected with said operating rod, a fixed stud, said actuating arm having pivotal connection with said stud, a spring for moving said actuating arm in one direction, and a cam connected with one of said feed rolls 40 and serving to move said actuating arm in the opposite direction.

23. In a machine of the character described, the combination with two gripper rolls, one above the other, and means for 45 feeding a folded tube thereto, of a cross-bar extending across the front of the machine adjacent the upper gripper roll, a plate rockably mounted on said cross-bar, two spreader arms depending from said cross-bar in front of the gripper rolls and having 50 pivotal connection at their upper ends with said plate, said arms being provided with coacting parts adapted to effect the movement of said arms toward and from each 55 other in the movement of one of said arms, an endwise movable rod connected with one of said arms, means for moving said rod in one direction, means for moving said rod in the opposite direction, and manually operable means connected with said plate for 60

rocking the same and thereby moving the spreader arms bodily outward from said gripper rolls.

24. In a machine of the character described, the combination with two gripper rolls, one above the other and means for feeding a folded tube thereto, of a cross-bar extending across the machine adjacent the upper gripper roll, a plate rockably mounted on said cross-bar, two spreader arms depending from said cross-bar and being pivotally connected at their upper ends to said plate, said arms being provided with coacting parts adapted to move said arms toward and from each other 75 when one of the arms is moved, an endwise movable rod connected with one of said arms, means for moving said rod in one direction, means for moving said rod in the opposite direction, a hand lever connected 80 with said plate so that the latter may be rocked for the purpose of moving the spreader arms bodily outward from said gripper rolls, a rock shaft, an arm secured to said rock shaft, a rod pivoted to said arm 85 adjacent its lower end and having its upper end connected with said hand lever, and means for operating said rock shaft.

25. A machine of the character described, comprising two gripper rolls, one above the other, means for feeding a bellows folded tube thereto, after the upper layer of the tube has been cut to provide a lip therein, said upper roll being provided with fixed cutting knives adapted to completely sever 95 the tube from the base of the lip outward through the side edges thereof, and with two sets of gripper fingers, one set being adapted to grip the lip at each side thereof and the other set being adapted to grip the 100 upper layer of the tube at points remote from the lip, said lower gripper roll being provided with a set of gripper fingers adapted to grip the lower layer of the tube and with a pivotally mounted knife adapted to 105 sever the lower layer of the tube from the portion of the tube previously passed through the gripper rolls, and means for actuating said several sets of gripper fingers for moving the same into opened and 110 closed positions, and means for actuating said pivotally mounted cutting knife.

26. A gripper roll having two gripper fingers located therein, said fingers being pivoted at their inner ends and having their outer ends projecting upward through openings in the gripper roll, spring means adapted to draw said fingers toward each other, means for moving said fingers apart, each gripper finger being provided at its outer 120 end with a pivotally mounted member having a gripping flange projecting over the edge of the opening through which the gripper finger extends, a spring connecting said member with the associated gripper finger, 125

- and a stop pin against which said member contacts for swinging the same about its pivot and drawing its gripping flange toward the outer surface of the gripper roll.
- 5 27. A gripper roll having two gripper fingers located therein and each having pivotal connection at one end and extending outward through openings provided in said roll, a spring connecting said fingers for 10 drawing the same toward each other, a rod rockably mounted in said roll, means interposed between said rod and said gripper fingers so that the latter will be moved apart upon the rocking of said rod in one direction, a spring for rocking the rod in the 15 opposite direction, and each gripper finger being provided at its outer end with a pivotally mounted member having a gripping flange adapted to project over the outer 20 surface of the gripper roll.
28. A gripper roll having two gripper fingers located therein, and each having pivotal connection at one end and having their outer ends projecting into openings provided in the outer surface of the gripper roll, 25 two pivotally mounted bell crank levers, one for each gripper finger and adapted when rocked in one direction to move the gripper fingers apart, a rod rockably mounted in said 30 roll, said rod being provided with means adapted to operate against said bell crank levers, and a spring for rocking said rod in one direction.
29. A gripper roll having two gripper 35 fingers located therein and having pivotal connection at their inner ends, their outer ends projecting outward through openings in said gripper roll, a spring connected with said gripper fingers for drawing the same 40 toward each other, each gripper finger being provided at its outer end with a gripping flange, a gripping dog located below each gripping flange and adapted to be moved toward and from the same, and means for 45 moving said gripper fingers and gripping dogs simultaneously.
30. A gripper roll having two gripper fingers therein, each having pivotal connection at its inner end and its outer end projecting outward through an opening in the 50 gripper roll, each gripper finger being provided at its outer end with a gripping flange, a gripping dog located below each gripping flange and adapted to be moved toward and from the same, means for actuating said 55 gripping fingers and gripping dogs in unison, and means adapted to prevent said gripping dogs from contacting with said gripping flanges when the latter are moved toward the former. 60
31. A gripper roll having two gripper fingers located therein and having pivotal connection with the gripper roll at their inner ends, the outer ends of the gripper fingers extending through openings in the 65 gripper roll, each gripper finger being provided at its outer end with a gripping flange, gripping dogs, one for each gripping flange and adapted to be moved toward and from the latter, a rod rockably mounted in the 70 gripper roll, and means interposed between said rod and said gripping fingers and dogs for moving the same toward and from each other in unison. 75
32. In a machine of the character described, the combination with two gripper rolls, one above the other, of a paste roll located below said gripper rolls, a roll in contact with the lower gripper roll, idler rolls in contact with said paste roll, a feed 80 roll below the latter, and guide wires extending between all of said rolls, the latter being provided with annular grooves to receive the same. 85
- In testimony that I claim the foregoing as my invention, I affix my signature in the presence of two witnesses, this 17th day of May, A. D. 1918.
